Primary Examiner — Cynthia R Underwood*(74) Attorney, Agent, or Firm* — Panitch Schwarze
Belisario & Nadel LLP(57) **CLAIM**

The ornamental design for a hinge, as shown and described.

DESCRIPTION

FIG. 1 is a top, front and left side perspective view of a hinge, in accordance with my new design;
FIG. 2 is a front elevational view thereof;
FIG. 3 is a rear elevational view thereof;
FIG. 4 is a left side elevational view thereof;
FIG. 5 is a right-side elevational view thereof;
FIG. 6 is a top plan view thereof;
FIG. 7 is a bottom plan view thereof; and,
FIG. 8 is a top, rear and right-side perspective view thereof.
Broken lines illustrate portions of the hinge that form no part of the claimed design.

1 Claim, 5 Drawing Sheets(56)
